United States Patent

Des. 236,996
Patented Sept. 30, 1975

236,996

INTERLOCKING PUZZLE

Parker S. Kennedy, 1628 La Loma Drive,
Santa Ana, Calif. 92705

Filed Mar. 22, 1974, Ser. No. 453,866

Term of patent 14 years

Int. Cl. D21—01

U.S. Cl. D34—15 M

FIG. 1.

FIG. 2.

FIG. 1 is a perspective view of an interlocking puzzle showing my new design; and

FIG. 2 is a side elevational view thereof, the side opposite being substantially identical.

I claim:

The ornamental design for an interlocking puzzle, as shown.
